WIRE TONGS FOR HOLDING OR DISPLACING
ENERGIZED CONDUCTORS OF TRANSMISSION LINES OR THE LIKE

Flavius Josephus Hendley, deceased, late of Chattanooga, Tenn., by Cornelia Smartt Hendley, executrix, Columbia, Tenn.

Application July 5, 1947, Serial No. 759,117

10 Claims. (Cl. 294—19)

1

The present invention relates to wire tongs for holding or displacing energized conductors of transmission lines or the like, and is particularly concerned with the provision of an improved wire tong or wire holder which, by virtue of its improved structure, is adapted to resist, without substantial distortion or breaking, a greater degree of tension, a greater degree of compression, or a greater force at right angles to the axis of the wire tong than the devices of the prior art.

Another object of the invention is the provision of an improved wire-holding device adapted to be used upon energized conductors of the type which includes a pair of jaws which may be moved toward each other or from each other by rotation of the supporting insulating pole, which includes an improved form of housing and guide mechanism for the movable jaw or hook by means of which bending stresses are transmitted to the supporting ferrule on the wooden pole at the outer edge of this ferrule, thereby greatly increasing the strength of the assembly.

Another object of the invention is the provision of an improved wire tong assembly which is sturdy, durable, adapted to be manufactured economically and assembled easily, and adapted to be used for a long period of time without necessity for replacement or repair of any of its parts.

Another object is the provision of an improved wire tong assembly including a fixed jaw and a movable jaw, the movable jaw being mounted with its threaded shank in a threaded member having a limited amount of universal motion whereby the movable jaw may be guided by its engagement with parts of the fixed jaw, the threaded members being self-aligning.

Other objects and advantages of the invention will be apparent from the following description and the accompanying drawings, in which similar characters of reference indicate similar parts throughout the several views.

Referring to the single sheet of drawings accompanying this specification,

Fig. 1 is a fragmentary side elevational view of the wire tong with the jaws in the open position.

Fig. 2 is a fragmentary front elevational view of the wire tong with the jaws in the open position.

Fig. 3 is a rear elevational view.

2

Fig. 4 is a fragmentary axial sectional view taken on the plane of the line 4—4 of Fig. 2, looking in the direction of the arrows.

Fig. 5 is a transverse sectional view taken on the plane of the line 5—5 of Fig. 1, looking in the direction of the arrows.

Fig. 6 is a transverse sectional view taken on the plane of the line 6—6 of Fig. 4, looking in the direction of the arrows.

10 Referring to Figs. 1 to 3, 10 indicates, in its entirety, the wire and tong assembly, which preferably includes an elongated insulating pole 11, a supporting ferrule 12, and a wire tong head 13. The wooden insulating pole 11 is preferably provided in its upper end with a cylindrical bore 14 into which the threaded shank 15 of the movable jaw member 16 may be retracted.

The pole is also provided with one or more transverse bores 17 located below the socket 14 for receiving the rivets 18 which pass through the pole and through the cylindrical flange 19 of the ferrule 12 and secure the ferrule fixedly on the end of the pole.

25 The ferrule 12 may consist of a cast metal member which is formed with an end wall 20 which may be substantially as thick as the threaded nut 21. The end wall 20 is preferably formed with an annular groove 22, leaving a radially projecting flange 23 at the top. Groove 22 is 30 defined by the lower surface 24 of flange 23, the cylindrical surface 25, and the annular surface 26.

The casting 12 is preferably made of some suitable light metal, such as an aluminum alloy, and, therefore, it is preferably provided with a washer 27 which may be made in the form of two halves, so that they can be assembled in the groove 22. Each of the halves is provided at each of its ends with a depending pin 28 which 40 slides into an axial aperture in the surface 26 of the end wall. The washer 27 may be made of brass.

The groove 22 is adapted to provide a rotatable support for the housing 29 of the tong head 13, and the housing 29 is preferably formed of a pair of housing halves 30, 31 (Fig. 2), which may be similar in construction, but are made in left-hand and right-hand members.

Each of the housing halves is provided with a 50 substantially half cylindrical lower end wall 32

3

which has an inwardly extending annular flange 33 (Fig. 4) adapted to extend into the groove 22 and substantially complementary to the space left in the groove 22 when assembled with washer 21 and another washer about to be described.

The housing halves 30, 31 are hollow, and thus are provided with space for the upper annular flange 23 on the ferrule. In order to provide the upper surface of the annular flange 33 with a different metal surface, another washer is preferably employed, indicated at 34, each washer comprising a half ring fitting against the surface 24 of the groove 22 and having a depending flange 35 which extends downward at the ends of the annular flange 33 so that the half washers 34 are supported in place by having their end flanges 35 engaged between the housing halves 30, 31 at their point of juncture, which comprises the two flat surfaces 36, 37 (Fig. 2).

In addition, the half washers 34 are confined by being inside the half housings, above the flange 33. The half housings 30 and 31 comprise tapered cast metal members which may each taper inwardly at 38 from the cylindrical lower end 32, and may be provided with a pair of substantially flat side walls 39 at the top, which portion of the side walls is substantially rectangular in cross-section, as seen in Fig. 1.

The housing halves are closed by a half front wall 40 and a half rear wall 41, and are formed with a half upper wall 42 which serves as one of the clamping members.

All of these half front and rear and upper walls extend over to the juncture which is formed by the flat surfaces 36 and 37, except that there is an axially extending slot 43 in the rear side of the housing 29 (Fig. 3) serving as a guide for a rearwardly extending web 44 which is carried by the upper movable clamping member 16.

This rear groove 43 is open at its upper end and extends downwardly to its base 46, which is located at such a point as to permit practically a full closure of the space between the movable jaw 16 and fixed jaw surface 42.

The front wall 40 also curves and extends diagonally inwardly at 47 (Fig. 4) and is bonded by a pair of side flanges 48, 49 (Fig. 4, Fig. 5) which are spaced to receive the pointed end portion 50 of the movable jaw 16. The upper wall 42 which forms the fixed clamping surface is also provided with a slot beginning at 51 (Fig. 4) and joining with the rear slot 43 to permit the neck portion 52 of the movable clamping member 16 to project upwardly from the housing 29.

To assure upper alignment of the housing halves, the one half 31 (Fig. 4) has a half circular groove 53, and located axially of the half housing on its surface 37 at the top wall 42, and the other half housing 30 has a complementary half cylindrical rib fitting in the groove 53.

The upper wall 42 is preferably curved on a radius which is equivalent to the radius of the largest conductor with which it is to be used.

The two housing halves 30, 31 are preferably secured together by a plurality of screw bolts 54, 55, 56 and 57 which pass through the housing half 30 and are threaded into threaded bores 58 in the housing half 31.

The movable clamping member or jaw 16 comprises a hook-shaped member which is provided with a threaded shank 15. The threaded shank 15 is preferably provided with strong, thick threads of rectangular cross-section complementary to the similar threads in the threaded bore 59 of the nut 21. The nut 21 is non-circular, that

is, substantially square in plan, as shown in Fig. 6, and it fits in a complementary socket 60 in the end wall 20 of the ferrule 12.

The socket 60, however, is provided with an overhanging lip or flange 61 at the upper side of nut 21, and the top surface of the nut may be made partially spherical at 62, cooperating with a complementary surface on the lower side of the lip or flange 61.

10 The nut 21 may have a loose fit in its socket, and may also be provided with a lower, radially extending flange 63 loosely fitted in a complementary recess 64 in the end wall 20. Thus the nut 21 is prevented from rotating, but is permitted a limited universal movement about its axis.

15 In order to assure the nut 21 being held in the end wall, it is engaged by a metal washer 64 on its lower side, the washer having an aperture for passing the threaded shank 15 and being engaged by the upper end of the pole 11.

20 At its upper end the threaded shank 15 supports a diagonally extending portion 65 of the movable jaw 16. This portion 65 extends rearwardly and out of the slot 43, and it has a curved upper surface 66. The portion 65 supports the rear web 44, which reinforces and aids in guiding the jaw 16, and it supports a pair of flanges 67, 68 extending laterally and upwardly at substantially right angles to the web 44.

25 30 The flanges 67, 68 are engaged on their rear sides by the portions 69 and 70 of the rear wall 41, which are located on either side of the slot 43. The web tapers outwardly, but has its base of sufficient width to be guided by the walls of the slot 43. The flanges 67, 68 fit in vertically extending grooves 71, 72 (Fig. 5) formed on the inside of the housing halves 30, 31, and thus are guided for vertical movement and reinforced against cantilever strains on the jaw 16. The movable jaw 16 has a substantially flat forward surface 73 and a curved clamping surface 74, which may be on the same curvature as the surface 42 of the fixed jaw.

35 40 The web 44 continues up over the top of the hook or jaw 16, having an upper portion 75 and a forwardly extending portion 76 on the front end 50 of the jaw 16. The pointed end portion 50 of the jaw 16 has a lower curved guiding surface 77 for guiding the conductor between the jaws, but the conductor is held between the jaws against removal, even though the jaws are loose, by the downwardly extending hump 78.

45 50 The upper portion of the movable jaw 16 also has laterally extending flanges 79 and 80 on both sides, thus giving it a T-shaped cross-section throughout, from the pointed tip 50 to the supporting portion 65, and increasing its strength against bending or deformation.

55 60 The operation of the wire tong head is as follows: The jaws are opened, as shown in Fig. 1, by turning the pole 11 counter-clockwise with respect to the movable jaw 16 which may be held in one hand. With the jaws open, the upper jaw 16 is hooked on the conductor on which it is to be used.

65 70 The weight of the tong itself causes the conductors to be engaged by the upper curved surface 74 of the hook 16 and holds the jaw against rotation while the operator turns the stick in a clockwise direction. This causes nut 21 to travel upward with respect to threaded shank 15, drawing the shank 15 into the socket 14 and bringing the two jaw clamping surfaces 74 and 42 closer together until the conductor is clamped between them. Then the pole 11 may be used for push-

ing or pulling or bending the energized conductor in any direction desired.

A pull is resisted by the strongly threaded shank 15, nut 21, and is transmitted directly to the pole 11 by the ferrule 12 and its upper wall 20. A push is taken by the upper surface 42 of the housing 29 and transmitted by the inwardly extending flange 33 directly to the upper wall 20 of the ferrule 12 on pole 11.

A lateral or cantilever force may be applied, and this is taken by the curved surface 42 and by the surface 73 on hook 16, and the hook is reinforced by having its side ribs 67 and 68 guided in grooves 71, 72 of the housing halves 30 and 31. Thus the strain from the hook is transmitted to the housing 29 and thence by means of the annular flange 33 and annular groove 22 from the housing 29 to the outer portions of the ferrule.

A very strong tong assembly is thus provided which will withstand all of these forces with a minimum possibility of deformation or breakage.

It will thus be observed that an improved wire tong has been invented which is stronger than any of the devices of the prior art, and which is simple in construction and adapted to be manufactured at a low cost. Its external appearance is streamlined, and it has no parts which might interfere with the action of its jaws, or which might catch on the conductors during the use of the tong.

The forces applied to the hook or movable jaw are immediately transmitted to the pole by means of a ferrule and a suitable housing, which reinforces the movable jaw and greatly increases the strength of the assembly. The universal movement of the threaded nut permits it to be self-aligning, and permits the movable jaw to react against the housing without placing a cantilever strain on the threaded shank.

While a preferred embodiment of the invention has been illustrated, many modifications may be made without departing from the spirit of the invention, and it is not wished to be limited to the precise details of construction set forth, but it is desired to take advantage of all changes within the scope of the appended claims.

Having thus described the invention, what is claimed as new and desired to be secured by Letters Patent of the United States is:

1. In a wire tong head, the combination of a ferrule adapted to be secured to a wooden pole or the like, said ferrule being provided with an upper wall having an annular groove, means carried by said ferrule and centrally located in its upper wall and provided with a threaded bore, a movable jaw having a threaded shank in said threaded bore, and a housing rotatably mounted in said annular groove and extending upwardly around said threaded shank and having sliding engagement with said movable jaw for permitting longitudinal sliding but resisting relative rotation between said housing and movable jaw, said housing having an upper clamping surface cooperating with said movable jaw to clamp a conductor.

2. In a wire tong head, the combination of a ferrule adapted to be secured to a wooden pole or the like, said ferrule being provided with an upper wall having an annular groove, means carried by said ferrule and centrally located in its upper wall and provided with a threaded bore, a movable jaw having a threaded shank in said threaded bore, and a housing rotatably mounted in said annular groove and extending upwardly

around said threaded shank and having sliding engagement with said movable jaw for permitting longitudinal sliding but resisting relative rotation between said housing and movable jaw, said housing having an upper clamping surface cooperating with said movable jaw to clamp a conductor, said housing being constructed of two parts secured together with securing means and each having an integral, inwardly extending annular flange engaging in said annular groove.

3. In a wire tong head, the combination of a ferrule adapted to be secured to a wooden pole or the like, said ferrule being provided with an upper wall having an annular groove, means carried by said ferrule and centrally located in its upper wall and provided with a threaded bore, a movable jaw having a threaded shank in said threaded bore, and a housing rotatably mounted in said annular groove and extending upwardly around said threaded shank and having sliding engagement with said movable jaw for permitting longitudinal sliding but resisting relative rotation between said housing and movable jaw, said housing having an upper clamping surface cooperating with said movable jaw to clamp a conductor, the opposed clamping surfaces on said movable jaw and housing being curved complementarily to the largest conductor with which the jaws are to be used.

4. In a wire tong head, the combination of a ferrule adapted to be secured to a wooden pole or the like, said ferrule being provided with an upper wall having an annular groove, means carried by said ferrule and centrally located in its upper wall and provided with a threaded bore, a movable jaw having a threaded shank in said threaded bore, and a housing rotatably mounted in said annular groove and extending upwardly around said threaded shank and having sliding engagement with said movable jaw for permitting longitudinal sliding but resisting relative rotation between said housing and movable jaw, said housing having an upper clamping surface cooperating with said movable jaw to clamp a conductor, said movable jaw being provided with axially extending, laterally projecting guide ribs, and said housing being provided with complementary guide slots for said ribs.

5. In a wire tong head, the combination of a ferrule adapted to be secured to a wooden pole or the like, said ferrule being provided with an upper wall having an annular groove, means carried by said ferrule and centrally located in its upper wall and provided with a threaded bore, a movable jaw having a threaded shank in said threaded bore, and a housing rotatably mounted in said annular groove and extending upwardly around said threaded shank and having sliding engagement with said movable jaw for permitting longitudinal sliding but resisting relative rotation between said housing and movable jaw, said housing having an upper clamping surface cooperating with said movable jaw to clamp a conductor, said threaded means carried by said ferrule having a limited universal movement in said ferrule but being secured against axial movement whereby cantilever strains are resisted by sliding engagement of the movable jaw and housing and are not applied to the threaded shank.

6. In a wire tong head, the combination of a ferrule adapted to be secured to a wooden pole or the like, said ferrule being provided with an upper wall having an annular groove, means carried by said ferrule and centrally located in its upper wall and provided with a threaded bore,

a movable jaw having a threaded shank in said threaded bore, and a housing rotatably mounted in said annular groove and extending upwardly around said threaded shank and having sliding engagement with said movable jaw for permitting longitudinal sliding but resisting relative rotation between said housing and movable jaw, said housing having an upper clamping surface cooperating with said movable jaw to clamp a conductor, said housing and ferrule being made of a light metal alloy, and said annular groove being aligned by washers of bearing metal above and below complementary parts on said housing.

7. In a wire tong, the combination of an elongated wooden insulating pole, said pole having a socket in its tool end, a ferrule having a cylindrical tubular body secured on the tool end of said pole, said ferrule having a thick end wall provided with an annular groove, said ferrule also having a socket located centrally of the upper wall of the ferrule, said socket being open at its top and bottom and having an overhanging flange at its upper side, a nut loosely mounted for a limited universal movement in said socket and engaging said flange, a washer engaging the lower side of said nut and secured between said thick wall and the end of said pole, a rotatable clamping member rotatively mounted on said ferrule but secured against axial movement, and a movable jaw having a threaded shank in said nut and mounted for sliding movement and having a sliding connection with said rotatable clamping member.

8. In a wire tong, the combination of an elongated wooden insulating pole, said pole having a socket in its tool end, a ferrule having a cylindrical tubular body secured on the tool end of said pole, said ferrule having a thick end wall provided with an annular groove, said ferrule also having a socket located centrally of the upper wall of the ferrule, said socket being open at its top and bottom and having an overhanging flange at its upper side, a nut loosely mounted for a limited universal movement in said socket and engaging said flange, a washer engaging the lower side of said nut and secured between said thick wall and the end of said pole, a rotatable clamping member rotatively mounted on said ferrule but secured against axial movement, and a movable jaw having a threaded shank in said nut and mounted for sliding movement and having a sliding connection with said rotatable clamping member, said rotatable clamping member comprising a pair of housing halves of lower cylindrical form having an inwardly extending annular flange engaging in said groove.

9. In a wire tong, the combination of an elongated wooden insulating pole, said pole having a socket in its tool end, a ferrule having a cylind-

rical tubular body secured on the tool end of said pole, said ferrule having a thick end wall provided with an annular groove, said ferrule also having a socket located centrally of the upper wall of the ferrule, said socket being open at its top and bottom and having an overhanging flange at its upper side, a nut loosely mounted for a limited universal movement in said socket and engaging said flange, a washer engaging the lower side of said nut and secured between said thick wall and the end of said pole, a rotatable clamping member rotatively mounted on said ferrule but secured against axial movement, and a movable jaw having a threaded shank in said nut and mounted for sliding movement and having a sliding connection with said rotatable clamping member, said movable jaw projecting upwardly and rearwardly from a slot between said housing halves and being provided with an upper hook formation for clamping a wire against the end surface of said rotatable clamping member.

10. In a wire tong, the combination of an elongated wooden insulating pole, said pole having a socket in its tool end, a ferrule having a cylindrical tubular body secured on the tool end of said pole, said ferrule having a thick end wall provided with an annular groove, said ferrule also having a socket located centrally of the upper wall of the ferrule, said socket being open at its top and bottom and having an overhanging flange at its upper side, a nut loosely mounted for a limited universal movement in said socket and engaging said flange, a washer engaging the lower side of said nut and secured between said thick wall and the end of said pole, a rotatable clamping member rotatively mounted on said ferrule but secured against axial movement, and a movable jaw having a threaded shank in said nut and mounted for sliding movement and having a sliding connection with said rotatable clamping member, said movable jaw projecting upwardly and rearwardly from a slot between said housing halves and being provided with an upper hook formation for clamping a wire against the end surface of said rotatable clamping member, said half housing members being provided with axially extending guide grooves, and said movable jaw being provided with guide ribs for sliding movement in said axial grooves whereby cantilever strains on said movable jaw are transmitted to said housing halves and by them transmitted to the periphery of the upper wall of said ferrule.

CORNELIA SMARTT HENDLEY.
Executrix of the Will of Flavius Josephus Hendley, Deceased.
